(57) **CLAIM**

The ornamental design for an exercise harness, as shown and described.

DESCRIPTION

FIG. 1 is a front elevational view of an exercise harness in accordance with our new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines in the figures are for the purpose of showing environmental structure, are for illustrative purposes only, and form no part of the claimed design.
